UNITED STATES PATENT OFFICE.

ELI P. NEWBANKS AND H. M. POWEL, OF LINCOLN, ILLINOIS.

IMPROVED SCAFFOLD.

Specification forming part of Letters Patent No. 50,437, dated July 17, 1866.

To all whom it may concern:

Be it known that we, ELI P. NEWBANKS and H. M. POWEL, of Lincoln, in the county of Logan and State of Illinois, have invented certain new and useful Improvements in Builders' and Painters' Scaffolds; and we do hereby declare that the following is a full, clear, and exact description of the same, reference being had to the accompanying drawings, and to the letters of reference marked thereon.

In the annexed drawings, making part of this specification, A represents the scaffold-board upon which the operator stands.

C C represent wires which have their ends securely fastened near the ends of the board A, said wires lying under the board, as shown. B B represent short boards or blocks, which are hinged on the under side of the board A at suitable distances apart. When these short boards are turned at right angles to the scaffold-board A they bear against the wires C, and serve to brace and support said scaffold-board, so that it will support the required weight upon it. In making the board A longer than required for ordinary use it may be hinged at the center. The ends of the board A, upon their under side, are provided with small pins, which are intended to stick into the platform which sustains it, to prevent it from slipping.

The brackets which form the platform for supporting the scaffold-board are made as follows: We take a piece of timber of the required width and length—say, six or eight inches wide and from two to three feet long—and frame into it an arm, E, and this arm we support by means of two braces, F F, running from the outer end of the arm to the lower end of the piece D. Pivoted in the timber D are four small rollers, m m, with their peripheries projecting beyond the timber, as shown. These rollers are covered with rubber or some similar material. The timber D stands in a vertical position, and the rollers m m rest against the walls of the house, their covering preventing defacing. There are two of these brackets, one for each end of the board A. The

ends of the board A rest upon the arms E E of the brackets.

G and H represent the supports for these brackets. These supports are made of two pieces of scantling, which are held together by means of the metallic collars K K, the said collars being made fast to one of the pieces, and the other piece sliding through the loop which they form.

To the lower piece, H, is secured a windlass with a ratchet-wheel and pawl attached. A cord passes around this windlass up the outside of piece H, then around a pulley, o, in its upper end, thence down a groove on its inner side, and secures to the lower end of the piece G. By this cord and windlass the piece G is easily raised and lowered or stationed in any desired position. The upper end of piece G rests in an opening made to receive it at the intersection of the arm E with the timber D, passing to said opening between the two braces F F.

In using this scaffold the brace H is placed at a bracing angle to the house, and the brackets with the scaffold-board upon them are raised and lowered, or stationed where required, by means of the windlass with its pawl and ratchet-wheel.

The brackets with their rollers easily run up and down the sides of the house without defacing it.

Having thus fully described our invention, what we claim as new, and desire to secure by Letters Patent, is—

The brackets as constructed, in combination with the scaffold-board A and braces H and G, the same being used substantially in the manner and for the purpose herein specified.

As evidence that we claim the foregoing we have hereunto set our hands in the presence of two witnesses.

ELI P. NEWBANKS.
HOWARD M. POWEL.
